[57] ABSTRACT

ABSTRACT

A machine for severing a strip into a plurality of strip segments, the strip having spaced reference indicia displayed thereon each at a selected distance from a corresponding position at which the strip is to be severed. The machine includes a cutter for severing the strip, a feed assembly for advancing the strip to the cutter, a probe for sensing the presence of any of the indicia at a selected position behind the cutter, and various switches for activating the feed assembly, deactivating the latter when the probe senses one of the indicia, activating the cutter when the feed assembly is deactivated, and deactivating the cutter after the strip has been severed.

FIG. 17

AUTOMATIC TAPE-FEED, INDEXING AND CUTTING MECHANISM

BACKGROUND OF THE INVENTION

The present invention relates generally to a machine for severing a strip into a plurality of strip segments of selected elongate extent, and more particularly to an automatic tape-feed, indexing and cutting machine for severing microfiche, other intelligence displaying plastic-like or paper strips, and strips in general which have displayed thereon spaced cut-reference indicia each at a selected distance from a corresponding position at which the strip is to be severed.

Machines of the above type are in general well known and include a cutter for severing the strip, a feed assembly for advancing the strip to the cutter, a probe for sensing the presence of any of the indicia on the strip at a selected position behind the cutter, and various switches for both activating and deactivating the feed assembly and cutter at selected intervals.

Conventional machines of the above type have a number of disadvantages associated with them and generally cannot timely sever the strip precisely. This often results in the necessity to discard imprecisely severed strip segments as waste. In this respect, in order for the machine to precisely sever the strip, it is preferable that the probe be capable of discriminating reference indicia whose purpose is to signal cutting operations from non-reference intelligence characters displayed on the strip between the indicia. This discriminating capacity is generally absent from such conventional machines.

It is also preferable that the probe and feed assembly be operatively associated with one another in such a manner that when the probe senses one of the indicia there is an immediate deactivation of the feed assembly so that a cut position on the strip is precisely at the cutter and not beyond the latter.

However, because of the inertia of the moving mechanical parts of the machine, and the absence of a rapid acting coupling system between the electronic circuitry of the probe and the mechanically moving parts, such conventional types of cutting machines have proven to be less than precise and are, therefore, unreliable.

Moreover, because of the nature of the mechanical parts themselves, for example, the gears which are interposed between the drive motor and the strip-contacting feed elements, i.e., drive rollers and the like, there is a certain degree of backlash associated with such gears which compounds the degree of error associated with such cutting machines.

Still another disadvantage associated with such machines is the fact that whenever the switch associated with the power supply is for some reason opened during the feeding cycle of the machine, the feed assembly reacts to terminate advancement of the strip to the cutter. Upon reactivation of the machine subsequently, the cutter will act to sever the strip at the position in which it remained at the time of the previous power shut down. This may result in the severing of the strip improperly between the positions at which the strip should have severed. As a result that portion of the strip must be discarded as waste.

SUMMARY OF THE INVENTION

Accordingly, it is an object of the present invention to provide an improved and novel automatic tape-feed, indexing and cutting mechanism which can discriminate cut-reference indicia from non-reference intelligence displayed on a tape or strip between the indicia.

It is another object of the present invention to provide such a machine in which there is arranged a mechanical coupling system interposed between the electronic circuitry of the probe and the strip-feeding elements which can effect a precise and immediate termination of the advancement of the strip when a cut-reference mark on the strip is sensed by the circuitry.

It is still another object of the present invention to provide such a machine in which the drive gears for the feed assembly are of greatly improved anti-backlash nature.

It is a further object of the present invention to provide such a machine in which the feed assembly after opening of the power switch will continue for a short period to advance the strip toward the cutter until the very next indexing mark on the strip is sensed by the machine probe.

The above objects, as well as other objects which will subsequently become clear, may be achieved by providing a machine which includes a cutter for severing the strip, a feed assembly for advancing the strip to the cutter, an improved probe for sensing the presence of any cut-reference indicia displayed on the strip at a selected position behind the cutter, and a probe control system for selectively rendering the probe alternately operative and inoperative at selected intervals during the operation of the feed assembly so that non-reference intelligence displayed on the strip other than and between the indicia will fail to be sensed by the probe during the inoperative intervals thereof. A number of SCR switches are associated with the feed assembly and cutter to precisely activate and deactivate the cutter and feed assembly at selected intervals. An improved anti-backlash gear assembly is provided for driving the feed assembly to substantially obviate "play" or backlash between the driven and driver gears.

BRIEF DESCRIPTION OF THE DRAWINGS

The foregoing and other objects, characteristics and advantages of the present invention will be more clearly understood from the following detailed description thereof when read in conjunction with the accompanying drawings, in which:

FIG. 1 is a schematic view in perspective of a roll of microfiche partially unwound;

FIG. 2 is a perspective view illustrating the machine pursuant to the present invention;

FIG. 3 is a schematic inverted plan view of the machine;

FIG. 4 is an elevational schematic view, partially in section, illustrating the feed and cutter actuating mechanism of the machine;

FIG. 5 is a schematic enlarged, plan view illustrating the association of the machine clutch and anti-backlash gear assembly;

FIG. 6 is an enlarged schematic plan view of the clutch shown generally in FIG. 5;

FIG. 7 is an inverted, elevational, further enlarged, schematic view illustrating the anti-backlash gear assembly;

FIG. 8 is an enlarged vertical cross-sectional view of the probe of the present invention;

FIG. 9 is a diagrammatic block diagram of the electrical control system of the present invention;

FIG. 10 illustrates the electrical circuitry of the probe and probe amplifier of the present invention;

FIG. 11 illustrates the electrical circuitry of a first time delay means of the present invention;

FIG. 12 illustrates electrical circuitry of a second time delay means pursuant to the present invention;

FIG. 13 illustrates electrical circuitry of a first inverter associated with the first time delay means pursuant to the present invention;

FIG. 14 illustrates electrical circuitry of a second inverter associated with the second time delay means pursuant to the present invention;

FIGS. 15 and 16 illustrate switching circuitry pursuant to the present invention; and

FIG. 17 illustrates feed-back switching means for overriding a power switch pursuant to the present invention.

DETAILED DESCRIPTION OF THE INVENTION

Referring now to the drawings, and more particularly to FIG. 1, the present invention relates to a device or machine which is adapted to sever elongate strips of plastic or paper and the like into a plurality of strip-segments each having a selected discrete length. In this respect, an example of the elongate strip to be severed is that of a roll of microfiche 20 wound upon a spool or core 22 and having displayed thereon intelligence 24 separated by laterally extending borders 26. The border 26 are illustrated schematically in phantom and represent those portions of the microfiche 20 which are to be severed by the device pursuant to the present invention. Extending along one longitudinal edge 28 of the microfiche 20 is a plurality of cut-reference indexing marks 30 which are separated from one another by respective ones of the laterally extending borders 26 by a uniform distance from the latter.

FIG. 2 illustrates the device pursuant to the present invention. The device is generally denoted by the reference character 32 and is provided with a housing 34 having an upper plate or platform 36. At one end portion of the platform 36 there is provided an enlarged cut-out 38 on each side of which extends one of a pair of upstanding brackets 40. Each of the brackets 40 is provided with a generally U-shaped slot 42 which is adapted to receive and support freely an axle portion 44 extending from respective ends of the spool 22 illustrated in FIG. 1.

Extending across the closed end of the enlarged cut-out 38 is an upper idler guide roller 46 beneath which is disposed a lower idler guide roller 48. The rollers 46 and 48 have horizontal axes, respectively, and are freely journalled together in a pair of upstanding brackets 49. Adjacent the rollers 46 and 48 is a pair of idler guide rollers 50 which have respective vertical axes and are spaced from one another by an extent corresponding to the length of the rollers 46 and 48, this in turn corresponding to the lateral extent of the microfiche 20 to be severed.

Extending forwardly from the vertical axis idler guide rollers 50 is a pair of track members 52 and 54 which

are likewise spaced from one another by an extent corresponding to the lateral extent of the microfiche 20. The track member 54 is provided with an upper elongate slot 56 having a toothed rack 58 (FIG. 4) disposed along the upper rail thereof. A probe 60 which is adapted to be adjustably positioned both longitudinally and laterally of the rack 58, and having a pinion gear 61 (FIG. 8) which meshes with the toothed rack 58, is adjustably mounted on the slotted track member 54 for sensing or detecting the presence or absence of respective ones of the indexing marks 30 on the microfiche 20.

A microfiche-feed assembly 62 is disposed at the forward end of the housing 34 and is provided with an upper presser roller 64 and a lower drive roller 66 (FIG. 4). The upper presser roller 64 is freely journalled in a spring-biased cantilevered bracket 68 which is pivotally arranged by means of a spring-hinge unit 70 (of conventional nature) upon a laterally extending overhead cross bar 72 spaced vertically above the upper plate or platform 36. A tension-control knob 74 is threadedly mounted upon a threaded vertical shaft (not shown) which is fixed to the cross bar 72 and extends through an appropriate slot (not shown) formed in the cantilevered bracket 68.

The overhead cross bar 72 is mounted upon a pair of supports 76, 78 each having a respective cut out 80 conforming to the cross-section of the cross bar 72. The cross bar 72 may, for example, be pivotally supported by means of a pin or the like (not shown) in the cut out 80 formed in the cross bar support 76. The opposite end of the cross bar 72 may be provided with a clamp-screw 82 which by conventional means (not shown) is adapted to tightly clamp that end of the cross bar 72 to the support 78 in the cut out 80 of the latter.

Extending laterally across the forward end of the housing 34 and mounted upon the upper cross bar 72 is an upper cutting blade 84 of stationary nature. The stationary blade 84 is presented with a cutting edge 85 (FIG. 4) which is spaced from the upper platform 36 by a distance corresponding to the thickness of the microfiche 20. A lower pivotal blade 86 is supported on a bracket 88 having a pivotal axis 90 (FIG. 3). The bracket 88 is pivotally journalled in respective overhanging portions 91 and 92 of the cross bar supports 76 and 78, respectively. Appropriate bearing assemblies 93 are provided in the overhanging portions 91 and 92 of the supports 76 and 78, respectively, to permit the blade support bracket 88, and thereby the pivotal blade 86, to pivot relative to the upper stationary blade 84.

Preferably, the pivotal axis 90 of the blade support bracket 88 is tilted slightly such that the cutting edge portion of the pivotal blade 86 adjacent the overhanging portion 92 is slightly elevated relative to that of the cutting edge portion of the pivotal blade 86 adjacent the overhanging portion 91. However, it is to be understood that the at-rest position of the cutting edge portion of the pivotal blade 86, even at its highest end, is to be no higher than the upper surface of the upper platform 36 so that the microfiche 20 can pass freely between the upper cutting blade 84 and the lower pivotal blade 86.

A control switch panel 94 is accessible upon the upper platform 36 to permit control over the various operations of the device 32 pursuant to the present in-

vention. Likewise, a counter 95 is disposed upon the upper platform 36 for indicating the number of cycles that the device 32 effects sequentially.

Referring now to FIG. 3, the underside of the platform 36 supports an electrical circuit board or housing 96 in which appropriate electrical circuitry, pursuant to the present invention, is disposed. A motor unit 98 having an output drive pulley 100 is likewise supported by the underside of the upper platform 36. The output drive pulley 100 is provided with a pair of belt grooves 102, 104. Associated with the belt groove 102 is a belt 106 which is coupled with a pulley 108 associated with a conventional clutch and speed reducer assembly 110. The output of the speed reducer 110 is coupled with a blade actuator 112 for effecting controlled pivotal movement of the lower blade 86 relative to the upper stationary blade 84.

The blade actuator 112 may be of any conventional type, for example, a cam and cam follower arrangement or the like. However, it is preferred that the blade actuator 112 be provided with, as illustrated in FIG. 4, an eccentric or drive crank 114 coupled with the output of the speed reducer 110, a first link 116 pivotally associated with the crank 114, and a second link 118 having one end thereof fixed to the blade support bracket 88 and the other end thereof pivotally associated with the link 116. For these purposes, a pin 120 couples the link 116 to the crank 114, whereas a pin 112 couples the link 116 with the link 118.

Referring again to FIG. 3, constrained within the belt groove 104 of the output drive pulley 100, is a second belt 124 which is associated with a pulley 126. The pulley 126 extends from and is associated with a clutch-brake and anti-backlash gear drive assembly 128. The assembly 128 is hingedly mounted on a support 130 fixedly suspended from the underside of the platform 36, and has a hinge axis 132 (shown in phantom). A worm wheel 134 concealed by the assembly 128 and driven by a worm in the assembly 128 (to be described below) is provided with an axle 136 upon which is concentrically mounted the drive roller 66. The platform 36 is provided with a cut out 138 through which the periphery of the drive roller 66 projects upwardly slightly for engagement with the microfiche 20 as the latter is spring biased or pressed thereagainst by the upper presser roller 64. An appropriate support bracket 140 is provided for the drive roller end of the axle 136, whereas the opposite end of the axle 136 is journalled in the support 130.

Referring now to FIG. 5, there is illustrated a schematic plan view of the clutch-brake and anti-backlash gear drive assembly 128. The assembly 128 is provided with a housing 160 having a cut out portion 162 straddling the support 130 upon which the assembly 128 is hingedly mounted. Provided coaxially with the hinge axis 132 in the housing 160 is a threaded bore 163 in which is threadedly constrained a socket ended set screw 164. The screw 164 tightly bears against one of a pair of ball bearing assemblies 166 disposed in opposite ends of the support 130 and which define the axis 132. The housing 160 is likewise provided with a cavity 168 in which is disposed a clutch brake unit 170. The unit 170 is provided with a flange 172 which is adapted to cover the end cavity 168 and is fastened to the housing 160 by means of respective screws 174 or the like. The housing 160 is likewise provided with an inner cavity 175 of reduced width in which extends a jaw clamp

piece 176 rotatably driven by the clutch-brake unit 170.

Also confined within the inner cavity 175 and separated from the clutch-brake unit 170 through the intermediary of a partition 177 or the like, is an anti-backlash gear drive unit 178. The unit 178 is provided with a worm 180 journalled freely in suitable bearings 182. In this respect, the worm 180 is axially hollow and is mounted upon a central shaft 184 by means of respective set screws 186, the central shaft 184 extending through the bearings 182 in the partition 177 into proximity with the jaw clamp piece 176 of the unit 170. A mating jaw clamp piece 188 is fastened to the end portion of the central shaft 184 by means of a set screw 190 or the like. The jaw clamp piece 176 of the unit 170 is slightly axially separable from the jaw clamp piece 188 of the unit 178 and is adapted to mesh with and rotate the jaw clamp piece 188 when driven by the clutch brake unit 170.

Referring now to FIG. 6, the clutch brake unit 170 is provided with a housing 192 upon which is fastened the flange 172 for securing the unit 170 to the housing 160 of the clutch-brake and anti-backlash gear drive assembly 128. The clutch-brake unit 170 is provided within its housing 192 with a pole system 194 and a coil system 196 for generating a magnetic field. A drive rotor 198 is rotatably journalled freely through the intermediary of a bearing assembly 200 in the housing 192 and projects partially out of the housing 192 so as to support the pulley 126 driven by the belt 124. The drive rotor 198, although freely journalled, is prevented by spacers 199 from undergoing axial movement relative to a driven rotor 202 mounted coaxially opposite and spaced from the drive rotor 198. The driven rotor 202 is rotatably journalled freely in the housing 192 through the intermediary of a bearing assembly 204.

Fixedly secured to and extending coaxially from the driven rotor 202 is a shaft extension 206. The shaft extension 206 extends into and is received by a bore 208 formed in the drive rotor 198. The diameter of the bore 208 in the drive rotor 198 is substantially larger than the diameter of the shaft extension 206 and, thus, the shaft extension 206 and drive rotor 198 are slidably associated with another. It is, therefore, possible for the drive rotor 198 to rotate relative to the shaft extension 206 of the driven rotor 202 when the latter is braked.

The drive rotor 198 is provided with an open cavity 210, whereas the driven rotor 202 is provided with a confronting open cavity 212. A compression spring 214 is concentrically mounted upon the shaft extension 206 and bears at one of its opposite ends against a spacer 216 supported on the shaft extension 206, within the cavity 210 of the drive rotor 198. The spring 214 bears at its other end against a spacer 218 which is associated slidably with a ball bearing assembly 228 confined within the cavity 212 of the driven rotor 202.

The driven rotor 202 is provided with an outer shaft portion 222 which is freely journalled in and projects through the ball bearing assembly 204. The extreme end of the outer shaft portion 222 supports the jaw clamp piece 176 which meshes with the jaw clamp piece 188 of the unit 178. In order to permit axial shifting of the driven rotor 202 into and out of contact with the drive rotor 198, the shaft extension 206 of the driven rotor 202 terminates sufficiently remote from the closed end of the bore 208. In the absence of a mag-

netic field generated by the coil 196, the spring 214 urges the driven rotor 202 into contact with a brake pad 224. However, when a magnetic field is generated, the magnetic field overcomes the strength of the spring 214 and causes the driven rotor 202 to approach, contact and rotate with the drive rotor 198. Upon dissipation of the magnetic field, the spring 214 again urges the driven rotor 202 against the brake pad 224 to effect termination of the rotation of the driven rotor 202, although the drive rotor 198 continues to rotate by the continuously rotating pulley 126. The axial spacing between the drive rotor 198 and driven rotor 202 is only slight. Therefore, the jaw clamp piece 176 fastened upon the outer shaft portion 222 of the driven rotor 202 is only slightly axially separable from the jaw clamp piece 188 of the unit 178 and always remains in the meshing association therewith.

Referring now to FIG. 7, there is illustrated the anti-backlash gear drive unit 178 in an inverted manner. The unit 178 includes the aforementioned bracket support 130 upon which is hinged the housing 160 for the entire clutch-brake and anti-backlash gear drive assembly 128. In this respect, the housing 160 is hingedly supported at the lower end portion (upper end portion as seen in FIG. 7) of the support bracket 130 at the bearing assembly 166. The support bracket 130 is likewise provided with a bearing assembly 242 which is coaxially mounted opposite a bearing assembly 244 in the support bracket 140 for the drive roller 66. The worm wheel 134 is mounted upon the worm wheel shaft 136 by means of a collar 248 integral with the worm wheel 134 and a set screw 250. The opposite end portions of the worm wheel shaft 136 are freely journaled in the bearing assemblies 242 and 244 of the support brackets 130 and 140, respectively. The drive roller 66 is press fit or otherwise conventionally secured to a hub 252. The hub 252 is secured to the shaft 136 such as by means of set screws 253.

The free end portion of the housing 160, which is hingedly supported upon the support bracket 130, is provided with an aperture 254 beneath which is concentrically arranged a threaded nut 256 of corresponding diameter, for supporting an adjustable thumb screw 258. The thumb screw 258 is provided with an aperture 260 at one end thereof in which is constrained one end of a tension spring 262. The opposite end of the spring 262 is secured to an aperture element or the like 264 provided in the upper platform 36.

Accordingly, the spring 262 acts to urge the housing 160 pivotally toward the upper platform 36 such that the worm 180 is spring-biased against and intermeshes with the teeth of the worm wheel 134. This spring-biased arrangement of the worm 180 and worm wheel 134 may be characterized as an anti-backlash gear drive system which obviates "play" and delimits clearance between the respective teeth of the worm 180 and worm wheel 184. Thus, whenever the worm 180 terminates rotation, the worm wheel 134 will be immediately responsive to the latter and without any backlash, the worm wheel 134 will likewise terminate its rotation.

Referring now to FIG. 8, there is illustrated the probe 60 pursuant to the present invention. In this respect, the probe 60 is adjustably supported both laterally and longitudinally of the track member 54, the latter having a base portion 280 affixed to the platform 36 and separated horizontally from the vertical portion in which is provided the rack 58. Thus, there is a clearance or

space between the base portion 280 and the vertical section which defines a lower slot 282. The probe 60 is provided with a light-detection housing 284 having a vertical section 286, an upper horizontal section 288 and a lower horizontal section 290. It is the lower horizontal section 290 which projects through the aforementioned lower slot 282 presented in the track member 54. The lower horizontal section 290 of the housing 284 is provided with a central bore 292 in which is constrained and press fit a plug 294 having an inclined end surface upon which a mirror 296 is supported at an angle of substantially 45°. The mirror 296 extends directly below an aperture 298 formed in the upper portion of the lower horizontal section 290. A photo-cell 300 fixedly projects into the central bore 292 for responding to light reflected by the mirror 296. Respective electrical leads or terminals 302 extend externally from the photo-cell 300 to appropriate electrical circuitry as will be described below.

20 The upper horizontal section 288 terminates in an end wall 304 in which is formed a semi-circular notch 306 for receiving and supporting a shaft 308 secured to the pinion 61. The vertical section 286 is provided with an aperture 310 which is coaxially opposite the semi-circular notch 306 for receiving freely the end portion of the shaft 308. A pair of spacers are provided one on each side of the pinion 61 so as to maintain the latter in an axially fixed position relative to the vertical section 286 of the housing 284.

25 30 A position-control and lamp support housing 314 is slidably mounted longitudinally but fixed laterally relative to the track member 54, the housing 314 acting to support the light-detection housing 284 upon the track member 54. The housing 314 is provided with a threaded front aperture 316 which communicates with an inner cavity 317. Threadedly fastened in the aperture 316 is a knob 318 having a threaded body 320 which abuts axially against the vertical end wall 304 of the upper horizontal section 288 of the housing 284.

35 40 The knob 318 is provided with a central bore 322 through which freely projects the shaft 308 for the pinion 61. The opposite end portion of the housing 314 is provided with a pair of end flanges 324 which conform in cross-section to the generally L-shaped cross-section of each of the portions of the upper slot 56 in the track member 54. It is the end flanges 324 which maintain the housing 314 upon the track member 54 so that the housing is longitudinally slidtable relative to the slot 56, but is restrained against lateral movement relative to the latter.

45 50 The lowermost portion of the housing 314 is provided with a cavity 326 in which is disposed a light source or lamp 328 having electrical leads or terminals 329 coupled with electrical circuitry as will be clarified below. Concentrically arranged upon the shaft 308 and extending externally of the housing 314 is a spacer 330. The spacer 330 is interposed between the knob 318 and a pinion control knob 332. The pinion control knob 332 is provided with a central bore 334 for receiving the shaft 308, and a threaded opening extending radially of the bore 334 for receiving a threaded set screw 338 to tightly secure the knob 332 to the end of the shaft 308.

55 60 65 Accordingly, it is possible to accurately position the aperture 298 formed in the lower horizontal section 290 of the housing 284 relative to the track member 54 for purposes of detecting selected ones of the indexing

marks 30 on the microfiche 20. In this respect, lateral adjustment of the light-detection housing 284 is effected simply by turning the knob 318. When the knob 318 is turned in one direction the end of the threaded body portion 320 of the knob 318 will engage the vertical end wall 304 of the upper horizontal section 288 of the housing 284. This will cause the spacers 312 to transmit an axial force against the pinion 61, thereby causing the pinion 61 to shift laterally of the rack 58. The pinion 61 is only shifted slightly relative to the rack 58 and, thus, the teeth of the pinion 61 always remain in intermeshing association with the teeth of the rack 58. Shifting of the pinion 61 laterally of the rack 58 also results in a shifting of the entire housing 284. The aperture 298 formed in the lower horizontal section 290 of the housing 284 is thereby shifted laterally relative to the rack 58 so that its position will be precisely disposed below a selected mark 30 on the microfiche 20. Longitudinal adjustment of the probe 60 is effected simply by turning the knob 332 which transmits rotary motion to the shaft 308 and thereby to the pinion 61. Rotation of the pinion 61 relative to the rack 58 will affect a longitudinal excursion of the probe 60 relative to the rack 58.

CONTROL SYSTEM

Referring now to FIG. 9, there is illustrated a diagrammatic block diagram of the electrical control system pursuant to the present invention. The control system is associated with a power supply 400 and includes a power switch 402. The power supply 400 may, for example, have a 110 output. The power switch 402 is electrically coupled with the motor 98 which acts to drive both the speed reducer assembly 110 and the clutch 170 which is associated with the anti-back-lash gear drive assembly 178. A power transformer 404 is also electrically coupled with the power switch 402 and acts to convert the AC power output into a 12 volt DC signal and a 35 volt DC signal. A pair of conventional rectifier, filter and voltage regulator systems 406 and 408 respectively, are electrically coupled with the secondary windings of the power transformer 404, the system 406 having a 12 volt output, and the system 408 having a 35 volt output.

Also electrically coupled with the power supply 400 is a TRIAC 410 whose output is electrically coupled with the motor 98 and the power transformer 404. The TRIAC 410 has the capacity to override the condition of the power switch 402 when the latter, for example, is open to maintain power to both the motor 98 and the power transformer 404.

The electrical control system further includes a first self-deactivating time delay circuit 412 having an automatic mode start switch 414. The time delay circuit 412 is coupled with and governs the operation of the probe 60 and, thus, at least in part may be characterized as a probe control means. The time delay circuit 412 is likewise electrically coupled with an inverter 416 which in turn is electrically coupled with a second self-deactivating time delay circuit 418. The inverter 416 acts to maintain the second time delay circuit 418 180° out of phase with the first time delay circuit 412. Thus, when the time delay circuit 412 is in a condition of operation, i.e., when the time delay circuit 412 is in a condition of delaying the operation of the probe 60, the inverter 416 acts to render the time delay circuit 418 inoperative.

The second time delay circuit 418 is electrically coupled with a second inverter 420 which in turn is electrically coupled also with the probe 60. The inverter 420 functions to render the probe 60 inoperative only when and only after the second time delay 418 has been activated for a selected interval and then deactivates itself.

Accordingly, when the first time delay 412 is activated by the automatic mode start switch 414, it renders the probe 60 inoperative for a selected interval. During this interval, the inverter 416 renders the time delay 418 inoperative and, thus, the output of the inverter 420 associated with the probe 60 has no effect on the latter. However, after the selected interval of operation of the first time delay 412, e.g., after the latter deactivates itself, the probe 60 is immediately activated. Likewise, the inverter 416 operates to activate the second time delay 418 for a second selected interval of reduced extent. However, the inverter 420 acts to maintain the probe 60 operative during the operation of the second time delay 418. When the second time delay 418 is rendered inoperative, e.g., when the latter deactivates itself after the second selected interval of reduced extent, the inverter 420 acts to defeat or render inoperative the probe 60.

The first time delay circuit 412 is also electrically coupled with a clutch feed SCR 422 (silicon control rectifier) which acts to activate the clutch 170 associated with the microfiche feed roller 66. The probe 60, on the other hand is electrically coupled with a clutch stop SCR 424 which acts to deactivate the clutch 170 associated with the microfiche feed roller 66. Moreover, the clutch feed SCR 422 and the clutch stop SCR 424 are operatively associated with one another such that when one is activated the other is deactivated. Thus, for example, when the clutch feed SCR 422 activates or engages the clutch 170, the clutch stop SCR 424 is deactivated. However, when the probe 60 senses one of the reference indexing marks 30 on the microfiche 20, it will activate the clutch stop SCR 424. The latter will in turn disengage the clutch 170 and deactivate the clutch feed SCR 422.

A manual stop feed switch 426 is electrically coupled with the probe 60 to effect a manual deactivation of the clutch 170, when desired, as is a second output from the inverter 420 which is electrically coupled with the clutch stop SCR 424 to activate the latter and, thereby, terminate feeding the microfiche 20 should the probe 60 fail to sense one of the indexing marks 30 during the selected interval of reduced extent and operation of the second time delay circuit 418. Thus, should the entire selected period of reduced extent transpire so that the time delay circuit 418 deactivates itself before the probe 60 senses one of the indicia 30 on the microfiche 20, then as a safeguard the second output of the converter 420 activates the clutch stop SCR 424 to effect termination of the microfiche feed.

The clutch feed SCR 422 is also electrically coupled with a third inverter 428 which in turn is electrically coupled with a pulse generator 430. The pulse generator 430 is electrically coupled with a TRIAC transformer 432 whose output or secondary winding is electrically coupled with the TRIAC 410. The inverter 428, pulse generator 430 and the TRIAC transformer 432 may be characterized as a feed-back loop to the TRIAC 410 to override an opening of the power switch 402 to

continue advancement of the microfiche 20 until the probe 60 senses a next mark 30.

The probe 60 is also coupled with a start cut SCR 434 which is adapted to activate the microfiche cutter blade 86 after the probe 60 or stop clutch SCR 424 has effected termination of the feeding or advancement of the microfiche 20. A stop cut switching means 436, preferably in the nature of a self-closing microswitch (although an SCR may be used likewise), is mechanically associated with a lobe (not shown) provided on the crank 114 which drives the cutting blade 86. Thus, when the blade 86 has effected severing of the microfiche strip 20, the switch 436 acts to deactivate or disengage the clutch of the speed reducer 110, thereby, deactivating the cutting blade 86. The stop cut switch 436 is also electrically coupled with the first time delay circuit 412 so as to activate the latter and effect an automatic second and further cycling of the machine after the microfiche has been severed. A cycle counter coil 438 is electrically coupled with the micro-switch 436, the counter indicator associated with the coil 438 being disposed on the platform 36 and designated by the reference character 95 in FIG. 2.

A manual cut switch 440 is interposed between and electrically coupled with the clutch feed SCR 422 and the start cut SCR 434 to permit an operator, independently of the probe 60, to effect a manual initiation of a cutting operation. The manual cut switch 440 is electrically associated with the clutch feed SCR 422 in such a manner that when the manual cut switch 440 is closed, the cutting blade 86 will not be actuated until the clutch stop SCR 424 effects termination of the advancement of the microfiche 20.

It will be understood, although not illustrated in FIG. 9, that the rectifier, filter and regulator system 408 whose output is 35 volts is electrically associated with the clutch feed SCR 422, the clutch stop SCR 424, the start clutch SCR 434, and the third inverter 428. On the other hand, the rectifier, filter and regulator system 406 whose output is 12 volts, is electrically associated with the probe 60, the first time delay circuit 412, the first inverter 416, the second time delay circuit 418, and the second inverter 420. For purposes of identification in FIG. 9, components associated with the system 408 are denoted by single asterisk. On the other hand, those components associated with the system 406 are denoted by a pair of asterisks.

PROBE AND PROBE AMPLIFIER

Referring now to FIG. 10, the electrical circuitry for the probe 60 is illustrated within the box P (broken line), and the amplification circuitry for the probe 60 is shown externally of the box P. The primary elements of the probe 60 are the photocell 300 and the lamp 328 associated with the photocell 300. A double-pole, double-throw, switch SW-1 is electrically coupled with the lamp 328 and may be moved between two extreme positions, namely the position in contact with the terminals T-1, as shown, and the position (not shown) in contact with the terminals T-2. A resistor R-1 is electrically coupled with photocell 300 in parallel therewith.

The nature of the circuitry of the probe 60 is conventional, the photocell 300 being adapted to distinguish either a darkly colored indexing mark 30 on a lightly colored field of the microfiche 20 or, alternatively, a lightly colored indexing mark 30 on a darkly colored

field of the microfiche 20. The switch SW-1, when in a position in contact with the terminals T-1, is in a condition for distinguishing a darkly colored indexing mark 30 relative to a lightly colored field of the microfiche 20. When the switch SW-1 is in contact with the terminals T-2, the photocell will distinguish a lightly colored indexing mark 30 from a darkly colored field of the microfiche 20.

A variable resistor R-2 (a potentiometer or the like) 10 is electrically coupled in a series with a resistor R-3, the resistors R-2 and R-3 being in parallel with a preferably 0.1 microfarad capacitor C-1 and a pair of Darlington transistor circuits Q-1 and Q-2. The resistor R-2 controls the sensitivities of the circuits Q-1 and Q-2. Each 15 of the Darlington transistor circuits Q-1 and Q-2 has an amplification factor of 10,000 or better and includes a pair of transistors whose collectors are commonly connected to one another. However, the emitter of one transistor of each pair is electrically coupled with the base of the second transistor of each pair, the emitter of the second transistor of each pair being electrically coupled to one another (to ground). Likewise, the collectors of each of the transistors of the circuit Q-1 and each of the transistors of the circuit Q-2 are electrically coupled to one another.

A normally closed switch SW-2 which corresponds to the manual stop feed switch 426 (FIG. 9) is electrically coupled with the commonly coupled emitters of the circuits Q-1 and Q-2 for purposes of deactivating the latter circuits in unison. The commonly coupled collectors of the circuits Q-1 and Q-2 are electrically coupled in parallel with a resistor R-4 and a resistor R-5 each having a rating of preferably 4.7K ohms. The resistor R-5 is electrically coupled with a base of a transistor Q-3 having an amplification factor in the range of, for example, 150-300, the collector of the transistor Q-3 being electrically coupled with a terminal of the lamp 328. The emitter of the transistor Q-3 is electrically coupled with a pair of RC networks which govern the activation of the clutch stop SCR 424, and the SCR 434. One RC network, which is associated with the clutch stop SCR 424, includes a capacitor C-2 and a resistor R-6 electrically coupled in parallel with one another, and a resistor R-8 and a diode D-1 coupled in series with one another, and together in parallel with the capacitor C-2 and resistor R-6. The other RC network, which is associated with the start cut SCR 434, includes a capacitor C-3 and a resistor R-7 electrically coupled in parallel with one another, and a resistor R-9 and a diode D-2 coupled in series with one another and together in parallel with the resistor R-7 and capacitor C-3. The capacitors C-2 and C-3 have, preferably, a rating of 5-15 microfarads, and the resistors R-6 and R-7 have, preferably, a rating of 5K ohms.

TIME DELAY CIRCUIT (412)

Referring now to FIG. 11, the time delay circuit 412 includes a pair of switches coupled in series with one another, namely a switch SW-3 mechanically associated with the micro-switch 436 (FIG. 9) which when opened and then closed will activate the time delay circuit 412, and a switch SW-4 (the automatic mode start switch 414 denoted in FIG. 9) which when closed will permit the time delay circuitry 412 to be continuously cyclically reactivated. A resistor R-10 is coupled in series with the switch SW-4 and is in turn electrically coupled in parallel with a resistor R-11 and a timecontroll-

ing variable resistor R-12, the latter having a maximum rating of 10K ohms.

A 100-150 microfarad capacitor C-4 is electrically coupled at one terminal with the variable resistor R-12, and at the other terminal with the resistor R-10 and a collector of a transistor Q-4 having an amplification factor of 150-300. The base of the transistor Q-4 is coupled with a resistor R-13 which is in turn electrically coupled in parallel with a resistor R-14 and a collector of a transistor Q-5 having an amplification factor of 150-300.

The base of the transistor Q-5 is electrically coupled with the capacitor C-4. The collector of the transistor Q-5 is likewise coupled in parallel with a 10K ohm resistor R-15 and a 5-15 microfarad capacitor C-5. A diode D-3 is coupled with the resistor R-15 and the capacitor C-5 and acts to channel current to the clutch feed SCR 422. The collector of the transistor Q-5 is also coupled with the inverter 416 as is the base of the transistor Q-4. The base of the transistor Q-4 and the collector of the transistor Q-5 are also commonly coupled with the base of the Darlington circuit Q-2 through the intermediary of a resistor R-40 and a diode D-20 coupled in series with one another.

Accordingly, the transistors Q-4 and Q-5 have an operative effect on the circuit Q-2 for determining when the transistor Q-3 will be fired to activate the clutch stop SCR 424 and the start cut SCR 434. When the transistor circuit Q-2 is "on" or activated by the transistors Q-4 and Q-5, the transistor Q-3 cannot activate the clutch stop SCR 424 and the start cut SCR 434. When the transistor circuit Q-2 is "off" or deactivated, then the transistor Q-3 can be activated to energize the SCR 424 and the SCR 434. However, the transistor Q-3 will not be activated until the transistor circuit Q-1 responds to the presence of an indexing mark 30 on the microfiche 20 as sensed by the photocell 300, and is in an "off" condition.

The transistors Q-4 and Q-5 operate 180° out of phase with one another (when one is off the other is on) and may be characterized as a mono-stable multivibrator whose output drives the clutch stop SCR 424 and the start cut SCR 434 and acts to defeat or inactivate temporarily the operation of the probe 60 due to the control it exercises over the transistor circuitry Q-2. Thus, when the capacitor C-4 discharges, the transistor Q-5 is deactivated and the transistor Q-4 is activated to in turn activate the transistor Q-2. When Q-2 is activated, the timing cycle of the time delay circuit 412 begins and prevents Q-3 from operating the clutch stop SCR 424 and the start cut SCR 434. When the capacitor C-4 is discharged, the transistor Q-5 is activated as is the transistor Q-3, and thereby the probe 60.

TIME DELAY CIRCUIT (418)

A second time delay circuit 418 is illustrated in FIG. 12 and includes a pair of transistors Q-6 and Q-7 each having an amplification factor of 150-300. The base of the transistor Q-6 is electrically coupled with the collector of the transistor Q-7 through the intermediary of a resistor R-16. The base of the transistor Q-7 is electrically coupled with the collector of the transistor Q-6 through the intermediary of a 100-150 microfarad capacitor C-6. The capacitor C-6 is electrically coupled with a time-controlling variable resistor R-17 having a maximum rating of 10K ohms, and at its other terminal with a resistor R-18. A resistor R-19 is electrically cou-

pled in parallel with the resistor R-17 at one side, and at the other side is electrically coupled in parallel with the resistor R-16 and the collector of the transistor Q-7. A 10K ohm resistor R-20 and a 5-15 microfarad capacitor C-7 are connected in parallel to the base of the transistor Q-6 and are together connected in series with a diode D-4 associated with the inverter 416 which is intermediate the time delay circuit 412 and the time delay circuit 418. The diode D-4 acts to channel current to the base of the transistor Q-6 and to the collector of the transistor Q-7. The collector of the transistor Q-7, the resistor R-16 and the resistor R-19 have a common junction which is coupled with the inverter 420. The transistors Q-6 and Q-7 operate in a manner similar to that of the transistors Q-4 and Q-5 (FIG. 11), but control the output of the inverter 420.

INVERTER (416)

Referring now to FIG. 13, there is illustrated the inverter 416 which is provided with a transistor Q-8 having an amplification factor of 150-300. The base of the transistor Q-8 is coupled in parallel with a series arrangement of a resistor R-21 and a diode D-5, and in parallel with a capacitor C-8. The resistor R-21 is associated with the junction of the resistors R-13 and R-14 in FIG. 11. The collector of the transistor Q-8 is activated by the regulator of the system 406 (FIG. 9) through the intermediary of a resistor R-22. The collector of the transistor Q-8 is also associated with the capacitor C-7 (FIG. 12). In operation, the inverter 416 acts to maintain the second time delay circuit 418 180° out of phase with the first time delay circuit 412 through the intermediary of the transistor T-8. Thus, when the transistor Q-5 is inactivated so are the transistors Q-8 and Q-6, the latter inactivating the second time delay circuit 418. When the transistor Q-5 is activated, the transistors Q-8 and Q-6 are activated, the transistor Q-6 initiating the timing cycle of the second time delay circuit 418 which lasts until the capacitor C-6 is discharged.

INVERTER (420)

Referring now to FIG. 14, there is illustrated a second inverter circuit 420 which includes a transistor Q-9 having an amplification factor of 150-300. The base of the transistor Q-9 is coupled in parallel with a capacitor C-9 and with a series arrangement of a resistor R-23 and a diode D-6. The resistor R-23 is associated with the junction of the collector of the transistor Q-7, the resistor R-16 and the resistor R-19 (FIG. 12). The collector of the transistor Q-9 is powered by the regulator 406 (FIG. 9) and is coupled in parallel with both the latter and a resistor R-42 connected in series with the regulator 406. A resistor R-24 is coupled in parallel with the resistor R-42 and in series with a diode D-7 which is electrically coupled with the base of the transistor circuit Q-2 (FIG. 10) for controlling the latter independently of the transistors Q-4 and Q-5 in FIG. 11.

Also coupled with the collector of the transistor Q-9 are a resistor R-41 having a 10K ohm rating, and a capacitor C-40 having a 5-15 microfarad rating and connected in parallel with the resistor R-41. A diode D-22 is connected to the resistor R-41 and capacitor C-40 and acts to channel current to the clutch stop SCR 424. Thus, when the transistor Q-9 is activated, namely when the second time delay circuit deactivates itself,

the transistor Q-9 will activate the transistor Q-2, thereby deactivating the probe 60, and will activate the clutch stop SCR 424 to terminate advancement of the strip 20. Since the clutch stop SCR 424 is coupled with the transistor Q-9 and not the start cut SCR 434, no cut will be effected upon termination of the advancement of the strip. Thus, the second time delay circuit 418 and the second inverter 420 act as a safeguard to terminate the feed of the strip 20 if no mark 30 is sensed by the probe 60 within the timing cycle of the delay circuit 418. This will prevent a machine "run-away".

CLUTCH FEED SCR (422) AND CLUTCH STOP SCR (424)

Referring now to FIG. 15, the clutch feed SCR 422 and the clutch stop SCR 424, each having a minimum blocking potential of 400 volts and a circuit commutated turn-off time of a maximum of 50 microseconds, are each coupled with a capacitor C-10 on opposite sides of the latter. The gate of the SCR 422 is electrically coupled with both the diode D-3 (FIG. 11) and a ground-channeling diode D-44 (FIG. 17). The gate of the SCR 424 is electrically coupled with the diode D-1 (FIG. 10) and with the diode D-22 (FIG. 14).

One side of the capacitor C-10 is coupled in parallel with the SCR 422 and with a coil L-1 of the clutch 170 (FIG. 6). The coil L-1 is also coupled in parallel with a capacitor C-11 and a variable resistor R-25. The variable resistor R-25 is coupled in parallel with the regulator 408 (FIG. 9) and a resistor R-26. The SCR 424 at one terminal is coupled in parallel with the capacitor C-10 and the resistor R-26. The SCR 422 and the SCR 424 are associated with one another in what may be characterized as a "flip-flop" arrangement. Thus, when the clutch feed SCR 422 is activated, the SCR 424 is deactivated. On the other hand, when the clutch stop SCR 424 is activated, the clutch feed SCR 422 is deactivated. In this manner, the clutch coil L-1 is alternately energized and deenergized by the SCR 422 and the SCR 424.

The manual cut switch 440 (FIG. 9) is also associated with the clutch feed SCR 422. In this respect, a 10K ohm resistor R-42 coupled in parallel with a 5-15 microfarad capacitor C-41 is coupled with the SCR 422 and a series arrangement of a diode D-42, a resistor R-43, a normally open manual switch SW-10 (440) and the gate of the start cut SCR 434. When the switch SW-10 is closed, the SCR 434 will be activated to initiate a cut, but only after the clutch stop SCR 424 is activated.

START CUT SCR (434)

Referring now to FIG. 16, the start cut SCR 434 is coupled in parallel with a capacitor C-12 and the coil L-2 of the clutch associated with the speed reducer 110 (FIG. 3). The gate of the SCR 434 is coupled in parallel with the diode D-2 (FIG. 10), to permit activation of the SCR 434 by the transistor Q-3 (FIG. 10), and also with the switch SW-10 (FIG. 15). A self-closing switch SW-5 (switch 436 in FIG. 9) is electrically coupled in parallel with one side of the capacitor C-12, a resistor R-27, a coil L-3 (coil 438) of the counter 95 and with a capacitor C-13. The other side of the resistor R-27 is coupled with a variable resistor R-28 which is connected in parallel with a capacitor C-14 and the coil L-2 associated with the clutch of the speed reducer

110. The resistor R-28 is also coupled with the regulator 408 (FIG. 9) to be powered by the latter.

Accordingly, when the transistor Q-3 (FIG. 10) is activated, the start cut SCR 434 is activated to power the coil L-2 which in turn engages the clutch of the speed reducer 110 and actuates the blade 86 for severing the strip 20. When the drive crank 114 associated with the cutting blade 86 effects one revolution, a lobe thereon (not shown) engages the switch SW-5 and opens it. Upon opening of the switch SW-5, the SCR 434 is deactivated and the coil L-2 is deenergized thereby terminating power to the cutting blade 86. Each time the switch SW-5 is opened, the coil L-3 associated with the counter 95 is energized once to define a particular cutting count.

INVERTER (428), PULSE GENERATOR (430) AND TRIAC TRANSFORMER (432)

Referring now to FIG. 17, there is illustrated a feed-back circuit associated with the clutch feed SCR 422 (FIG. 15) for powering the motor 98 and the transformer 404 until the probe 60 senses one of the indicia 30 on the strip and terminates the advancement of the strip 20. The feed-back loop, thus, acts independently of the power switch 402 (FIG. 9) and continues to operate the motor 98 and the transformer 404 even when the power switch 402 is opened until the probe 60 senses one of the indicia 30 on strip 20.

In this respect, the feed-back loop comprises the third inverter 428, the pulse generator 430 and the TRIAC transformer 432, each denoted in FIG. 17 by a respective box in broken line. The inverter 428 includes a transistor Q-10 having an amplification factor of 150-300 and whose base is coupled in parallel with a capacitor C-15, and a diode D-21 and a resistor R-29. The resistor R-29 is in series with the junction of the coil L-1 and the capacitor C-10 in FIG. 15. The collector of the transistor Q-10 is coupled with a resistor R-30 and is powered by the regulator 408 (FIG. 9).

The pulse generator 430 includes a pair of transistors Q-11 and Q-12 each having an amplification factor of 150-300 and respective collectors which are coupled to opposite sides of a primary winding 432-P of the transformer 432. The collectors of the transistors Q-11 and Q-12 are also coupled with a pair of capacitors C-16 and C-17, the capacitor C-16 being coupled with the base of the transistor Q-11 and the capacitor C-17 being coupled with the base of the transistor Q-12. The primary winding 432-P of the transformer 432 is also electrically coupled with both the resistor R-30 and the collector of the transistor Q-10 of the inverter 428. One side of the secondary winding 432-S of the transformer 432 is electrically coupled with the gate of the TRIAC 410, whereas the other side of the secondary winding 432-S is coupled with a primary terminal of the TRIAC 410. The latter said terminal of the TRIAC 410 and an opposite terminal of the TRIAC 410 are coupled in parallel with the power switch 402, the motor 98, and the primary winding of the power transformer 404. The pair of secondary windings of the power transformer are coupled, respectively, with the systems 406 and 408. The power supply 400 is within a loop defined by the switch 402 and the motor 98.

Accordingly, should the switch 402 be closed, it shorts out and inactivates the TRIAC 410. However, should the switch 402 be opened during a feeding cycle, the TRIAC 410 will override the opened switch

402 and will continue to power the clutch feed SCR 422 until a mark 30 on the strip 20 is sensed by the probe 60, or until the second time delay circuit deactivates the clutch stop SCR 424.

A switch SW-12 is mechanically coupled with the switch 402 and operates 180° out of phase with the latter. Thus, when the switch 402 is opened, the switch SW-12 closes and directs current from a diode D-44 associated with the gate of the clutch feed SCR 422, and current from a diode D-45 associated with the gate of the start cut SCR 434, to ground. This will prevent the cutter from severing the strip 20 when the switch 402 is opened during a feeding cycle, but will permit the feeding cycle to continue until the probe 60 senses a mark 30 or is overridden by the second time delay circuit 418.

PARAMETERS

It will be understood that certain components discussed above have preferred characteristics or parameters within the ranges defined. The other components may have a wide variety of characteristics, although not defined above, but which may be easily determined by being properly balanced with those defined, by artisans skilled in the art.

OPERATION OF THE MACHINE

A roll of microfiche 20 is first disposed across the slot 38 in the upper platform 36 so that the opposite ends thereof rest in the brackets 40. The strip is partially unwound from the roll and is threaded between the guide rollers 48 and 49. The microfiche 20 is then pulled between the tracks 52 and 54 and threaded between the upper presser roller 64 and the lower drive roller 66. The microfiche 20 is then pushed forwardly so that it passes below the cutting edge of the upper stationary blade 84. Then one of the lateral borders 26 is aligned with the cutting edge of the upper blade 84, and the longitudinal position of the probe 60 is adjusted by means of the knob 332 so that the aperture 298 beneath the lamp 328 coincides with the position of one of the indexing marks 30 which immediately trails the lateral border 26 oriented with the cutting edge of the upper blade 84. Then, by means of the knob 318 the lateral position of the aperture 298 beneath the lamp 328 is adjusted so that it also corresponds in position to whatever distance the first trailing indexing mark 30 is spaced from the edge 28 of the microfiche 20.

The power switch 402 associated with the motor 98 and the power transformer 404 is then closed to power each of the latter, as is the automatic start switch 414 (switch SW-4 in FIG. 11). The time delay circuit 412 and the clutch feed SCR 422 will thereby be actuated simultaneously. Upon actuation of the time delay circuit 412, the probe 60 will be rendered inoperative for a selected period as determined by the parameters of the time delay circuit 412, e.g., the setting of the variable resistor R-12, so that it cannot respond to any intelligence which may lie along the edge 28 of the microfiche 20 between the marks 30. During this initial inoperative period of the probe 60, the clutch feed SCR 422 energizes the coil L-1 of the clutch 170 so that the clutch 170 is engaged and transmits power to the worm 180. The clutch 170 is engaged when the drive rotor 198 is engaged by the axially shiftable driven rotor 202 due to the excitation of the coil 196 (L-1).

Because of the provision of the support housing 160 which is pivotal relative to the bracket 130 (FIG. 7) and the spring 262 which urges the free end of the housing 160 downwardly so that the worm 180 journaled in the housing 160 is biased against the worm wheel 134, the worm wheel 134 is always immediately responsive to the worm 180. Thus, there is absent any "play" or backlash between the teeth of the worm wheel 134 and the worm 180. Accordingly, when the worm 180 is driven, the worm wheel 134 immediately responds and transmits rotation to the lower drive roller 66 which in turn frictionally advances the microfiche 20 toward the cutters 84 and 86.

During the period of operation of the first time delay circuit 412, the inverter 416 renders the second time delay circuit 418 inoperative so that it cannot effect the condition of the probe 60. When the next indexing mark 30 begins to closely approach the probe 60, the first time delay circuit 412 deactivates itself pursuant to the setting of the resistor R-12 thereby activating the probe 60. The inverter 416 will in turn activate the second time delay circuit 418 which works through the intermediary of the inverter 420 to permit operation of the probe 60 for a selected period of lesser duration than the interval during which the probe 60 is rendered inoperative by the first time delay circuit 412.

Once the probe 60 has been activated, the clutch stop SCR 424 is activated to thereby disengage the driven rotor 202 of the clutch 170 from the drive rotor 198. The spring 214 urges the driven rotor 202 into abutment with the brake pad 224 to thereby terminate rotation of the driven rotor 202. Upon the termination of rotation of the driven rotor 202 the worm 180 is likewise stopped. Again, because of the provision of the pivotal or hinged housing 160 which supports the worm 180, and the spring 262 which urges the worm 180 into contact with the worm wheel 134, there is absent clearance between and backlash of the worm wheel 134 relative to the worm 180. This effects an immediate termination of the rotation of the lower drive roller 66. This in turn immediately stops the advancement of the microfiche 20.

The start cut SCR 434 is then activated to in turn energize the coil L-2 associated with the clutch of the speed reducer 110. This will effect a single revolution of the drive crank 114 and an uplift of the lower pivotal blade 86 relative to the stationary blade 84. The strip 20 is thereby severed. When the blade 86 returns to its at-rest position, as illustrated in FIG. 4, the crank 114 is returned to its initial position, and the lobe (not shown) on the crank 114 acts to open the self-closing micro-switch SW-5, e.g., the stop cut switch 436 in FIG. 9, and the switch SW-3 which are mechanically coupled with one another to open or close in unison. The switch SW-3, when closed (FIG. 11), acts to initiate a second and further cycle of the device by reactivating the first time delay circuitry 412.

If, for some reason, no indexing mark 30 appears within the period of operation of the second time delay circuit 418, for example the manufacturer of the microfiche failed to provide one of the indexing marks 30 in its proper position, then the second time delay circuit 418 through the intermediary of the inverter 420 deactivates the probe 60 and activates the clutch stop SCR 424. This in turn deenergizes the coil L-1 of the clutch 170 and effects termination of the rotation of the worm 180, the drive worm wheel 134 and the lower driver

roller 66. This prevents an uncontrolled "runaway" of the machine and permits operator inspection of the microfiche 20.

A manual stop feed switch 426 (SW-2 in FIG. 10) is associated with the amplification circuitry of the probe 60 to permit manual termination of the advancement of the microfiche 20 when desired. The switch SW-2 when opened will deactivate both of the transistor circuits Q-1 and Q-2 thereby activating the transistor Q-3 to in turn activate the clutch stop SCR 424. A switch SW-11 (FIG. 10) is mechanically coupled with the switch SW-2 and operates 180° out of phase with the latter. Thus, when the switch SW-2 is opened, the switch SW-11 is closed thereby grounding the gate of the start cut SCR 434 and preventing the latter from effecting a cut of the microfiche.

Likewise, a manual cut switch 440 is associated with the start cut SCR 434 to permit a manual cutting operation, the switch 440 (FIG. 9) being associated with the clutch feed SCR 422 in a manner such that even when the switch 440 is closed it will not effect a cutting operation until the clutch stop SCR 424 has effected termination of the advancement of the microfiche 20, e.g., until the probe 60 senses one of the indexing marks 30.

Having thus set forth the nature of the invention, it will be understood that numerous alterations of the structure herein disclosed will suggest themselves to those skilled in the art. However, it is to be understood that the present disclosure relates to a preferred embodiment of the present invention which is for purposes of illustration only and not to be construed as a limitation of the invention.

What is claimed is:

1. In a machine for severing a strip into a plurality of strip segments of selected elongate extent, the strip having spaced reference indicia displayed thereon each at a selected distance from a corresponding position at which said strip is to be severed, the machine including cutting means for severing said strip, feed means for advancing said strip to said cutting means, probe means for sensing the presence of any of said indicia at a selected position behind said cutting means, first switching means operatively associated with said feed means for activating the latter, second switching means operatively associated with said probe means and said feed means for deactivating the latter when said probe means senses one of said indicia, third switching means operatively associated with said probe means and said cutting means for activating the latter when said probe means senses one of said indicia, and fourth switching means operatively associated with said cutting means for deactivating the latter when said strip is severed, an improvement comprising:

probe control means for selectively rendering said probe means alternately operative and inoperative at selected intervals during the operation of said feed means so that intelligence displayed on said strip other than and between said indicia will fail to be sensed by said probe means during the inoperative intervals of the latter, said probe control means including timing means operatively associated with said second switching means for activating the latter to deactivate said feed means when said probe means fails to sense one of said indicia within a selected time period during its operative interval.

2. In a machine as claimed in claim 1, wherein said probe control means includes a self-deactivating first time delay means operatively associated with said feed means and said probe means for deactivating the latter for a selected period during the operation of said feed means.

3. In a machine as claimed in claim 2, wherein said first time delay means includes means for deactivating said probe means simultaneously upon activation of said feed means.

4. In a machine as claimed in claim 2, wherein said timing means of said probe control means includes a self-deactivating second time delay means operatively associated with said first time delay means and said probe means for permitting said probe means to operate for a selected period of reduced extent during the operation of said feed means after said first time delay means is deactivated.

5. In a machine as claimed in claim 4, including first inverter means interposed between and operatively associated with said first and second time delay means for alternately rendering said second time delay means inoperative and operative when said first time delay means is activated and deactivated, respectively.

6. In a machine as claimed in claim 5, including second inverter means interposed between and operatively associated with said second time delay means and said probe means for deactivating the latter immediately after termination of said selected period of reduced extent of the operation of said second time delay means.

7. In a machine for severing a strip into a plurality of strip segments of selected elongate extent, the strip having spaced reference indicia displayed thereon each at a selected distance from a corresponding position at which said strip is to be severed, the machine including cutting means for severing said strip, feed means for advancing said strip to said cutting means, probe means for sensing the presence of any of said indicia at a selected position behind said cutting means, first switching means operatively associated with said feed means for activating the latter, second switching means operatively associated with said probe means and said feed means for deactivating the latter when said probe means senses one of said indicia, third switching means operatively associated with said probe means and said cutting means for activating the latter when said probe means senses one of said indicia, and fourth switching means operatively associated with said cutting means for deactivating the latter when said strip is severed, an improvement comprising:

a. probe control means for selectively rendering said probe means alternately operative and inoperative at selected intervals during the operation of said feed means so that intelligence displayed on said strip other than and between said indicia will fail to be sensed by said probe means during the inoperative intervals of the latter;

b. a manual power switch for powering said machine from an external electrical power supply; and

c. feed-back power means for bypassing said power switch when the latter is opened during advancement of said strip by said feed means to power the latter until said probe means next senses one of said indicia.

8. In a machine as claimed in claim 7, wherein said feed-back power means includes a TRIAC, said exter-

nal electrical power supply and power switch being coupled in series and together coupled in parallel with said TRIAC, and including a motor operatively associated with said feed means for driving the latter, said motor being coupled in parallel with said TRIAC and said in-series coupled external electrical power supply and power switch.

9. In a machine as claimed in claim 3, wherein said probe means includes a photocell for responding to said indicia with a voltage drop, first transistor circuit means coupled with said photocell for responding to and being deactivated by a decrease in voltage across said photocell, second transistor circuit means coupled with said first transistor circuit means and said first time delay means for being deactivated by the latter when the latter is deactivated, and third transistor circuit means coupled with both said first and second transistor circuit means for being activated when both said first and second transistor circuit means are deactivated, said second and third switching means being coupled with said third transistor circuit means to be activated by the latter and, thereby, deactivate said feed means and activate said cutting means, respectively.

10. In a machine as claimed in claim 9, wherein said first and second transistor circuit means each includes a pair of transistors whose collectors are all mutually coupled with one another, said third transistor circuit means including a single transistor whose base is coupled with the mutually coupled collectors of each of said pairs of transistors, the emitter of one transistor in each of said pairs being coupled with the base of the other transistor in each of said pairs, the emitter of the other transistor in one of said pairs being coupled with the emitter of the other transistor in the other of said pairs.

11. In a machine as claimed in claim 10, including a light source operatively associated with said photocell, said single transistor having a collector coupled with a terminal of said light source, and an emitter coupled with said second and third switching means.

12. In a machine as claimed in claim 11, including a first resistor and a first capacitor coupled in parallel with one another and together in a series with a terminal of said second switching means, a second resistor and a second capacitor coupled in parallel with one another and together in series with a terminal of said third switching means, and a third capacitor coupled in parallel with said first transistor circuit means and said photocell.

13. In a machine as claimed in claim 9, wherein said first time delay means includes a pair of transistors, and a time-controlling variable resistor having a pair of opposite terminals, one of said terminals being coupled with a base of one of said transistors, the other of said terminals being coupled with a collector of each of said transistors and with a base of the other transistor.

14. In a machine as claimed in claim 13, including a capacitor interposed between and coupled with the base of said one of said transistors and with the collector of said other of said transistors.

15. In a machine as claimed in claim 14, wherein the collector of said one of said transistors and the base of said other of said transistors are coupled with said second transistor circuit means and with said first switching means.

16. In a machine as claimed in claim 15, including a resistor and a further capacitor coupled in parallel with one another and together in series with and between said collector of said one of said transistors and said first switching means.

17. In a machine as claimed in claim 16, including a self-closing switch coupled at one terminal with an emitter of each of said transistors, and at its other terminal with the collector of said other of said transistors and through the intermediary of the first said capacitor to the base of said one of said transistors, said switch when opened and then closed acting to activate said other of said transistors and, thereby, initiate a timing cycle.

18. In a machine as claimed in claim 13, wherein said probe control means includes a self-deactivating second time delay means operatively associated with said first time delay means and said probe means for permitting said probe means to operate for a selected period of reduced extent during the operation of said feed means after said first time delay means including a second pair of transistors, and a second time controlling variable resistor having a pair of opposite terminals, one of the latter said terminals being coupled with a base of one of said transistors of the latter said pair, the other of the latter said terminals being coupled with a collector of each of said transistors of the latter said pair and with a base of the other transistor of the latter said pair.

19. In a machine as claimed in claim 9, wherein each of said first and second switching means includes a respective silicon control rectifier, each of said rectifiers having a pair of terminals similar to the other and a gate, one terminal of one of said rectifiers which corresponds to one terminal of the other rectifier being coupled with the latter through the intermediary of a capacitor, the other terminal of each of said rectifiers being coupled with one another, the gate of said one said rectifiers being coupled with said third transistor circuit means, the gate of said other rectifier being coupled with said first time delay means, and including a clutch coil for generating a magnetic field, said clutch coil having a pair of opposite terminals coupled in parallel with said capacitor.

20. In a machine as claimed in claim 19, wherein said third switching means includes a silicon control rectifier, and said fourth switching means includes a mechanically actuatable switch, the latter said rectifier including a pair of terminals and a gate, one of the latter said terminals being coupled with one terminal of the latter said switch through the intermediary of a further capacitor, the other terminal of the latter said rectifier and of the latter said switch being coupled with one another, said gate of the latter said rectifier being coupled with said third transistor circuit means, and including a further clutch coil for generating a magnetic field, the latter said clutch coil being coupled in parallel with the latter said capacitor.

21. In a machine for severing a strip into a plurality of strip segments of selected elongate extent, the strip having spaced reference indicia displayed thereon each at a selected distance from a corresponding position at which said strip is to be severed, the machine including cutting means for severing said strip, feed means for advancing said strip to said cutting means, probe means for sensing the presence of any of said indicia at a selected position behind said cutting means, first switch-

ing means operatively associated with said feed means for activating the latter, second switching means operatively associated with said probe means and said feed means for deactivating the latter when said probe means senses one of said indicia, third switching means operatively associated with said probe means and said cutting means for activating the latter when said probe means senses one of said indicia, and fourth switching means operatively associated with said cutting means for deactivating the latter when said strip is severed, an improvement comprising:

probe control means for selectively rendering said probe means alternately operative and inoperative at selected intervals during the operation of said feed means so that intelligence displayed on said strip other than and between said indicia will fail to be sensed by said probe means during the inoperative intervals of the latter,

said probe control means including a self-deactivating first time delay means operatively associated with said feed means and said probe means for deactivating the latter for a selected pe-

riod during the operation of said feed means, and a self-deactivating second time delay means operatively associated with said first time delay means and said probe means for permitting said probe means to operate for a selected period of reduced extent during the operation of said feed means after said first time delay means is deactivated; first inverter means interposed between and operatively associated with said first and second time delay means for rendering each 180° out of phase with the other and, thereby, alternately rendering said second time delay means inoperative and operative when said first time delay means is activated and deactivated, respectively; and second inverter means interposed between and operatively associated with said second time delay means and said probe means for rendering each 180° out of phase with the other and, thereby, operating said probe means during the time-delaying operation of said second time delay means.
